US00D923390S

(12) **United States Design Patent** (10) **Patent No.:** **US D923,390 S**
(45) **Date of Patent:** **** Jun. 29, 2021**

(54) **RICE MILLING MACHINE**

(71) Applicant: **LG ELECTRONICS INC.**, Seoul (KR)

(72) Inventors: **Hyunhee You**, Seoul (KR); **Sungkyung Kim**, Seoul (KR); **Joo-Gyeom Kim**, Seoul (KR); **Kyoungmin Baek**, Seoul (KR); **Woonkyu Seo**, Seoul (KR); **Hyunsun Yoo**, Seoul (KR); **Yousook Eun**, Seoul (KR); **Hyejin Choi**, Seoul (KR)

(73) Assignee: **LG ELECTRONICS INC.**, Seoul (KR)

(**) Term: **15 Years**

(21) Appl. No.: **29/678,164**

(22) Filed: **Jan. 25, 2019**

(51) LOC (13) Cl. **31-00**

CLAIM

The ornamental design for a rice milling machine, as shown and described.

DESCRIPTION

FIG. 1 is a front, right side, perspective view of a rice milling machine showing our new design;

FIG. 2 is a front view thereof;

FIG. 3 is a rear view thereof;

FIG. 4 is a left side view thereof;

FIG. 5 is a right side view thereof;

FIG. 6 is a top view thereof; and,

FIG. 7 is a bottom view thereof.

The broken lines shown in the figures depict portions of the rice milling machine that form no part of the claimed design.

1 Claim, 7 Drawing Sheets
